UNITED STATES PATENT OFFICE.

EDWARD RANSOM THOMPSON, OF PANAMA CITY, FLORIDA.

SPRING.

1,178,605.

Specification of Letters Patent. Patented Apr. 11, 1916.

Application filed November 4, 1914. Serial No. 870,252.

To all whom it may concern:

Be it known that I, EDWARD RANSOM THOMPSON, a citizen of the United States, residing at Panama City, in the county of 5 Bay and State of Florida, have invented certain new and useful Improvements in Springs, of which the following is a specification, reference being had to the accompanying drawings.

10 This invention relates to certain improvements in springs and has relation more particularly to a novel and improved spring adapted for use as a stop in connection with doors or other movable bodies and wherein 15 a portion of said spring is offset laterally to the remainder of the spring so that an unobstructed compression thereof may be effected.

With these and other objects in view, my 20 invention consists in the novel construction, combination, and arrangement of parts to be hereinafter more fully described, claimed, and illustrated in the accompanying drawing, in which,

25 Figure 1 is a vertical sectional view showing my improved device connected to a door frame; Fig. 2 is a sectional view on the line 2—2 of Fig. 1; Fig. 3 is a rear elevational view of a door frame showing the stop strips 30 connected thereto; and Fig. 4 is a perspective view of one of the springs used in connection with one of the stop springs.

Referring more particularly to the drawing, the numeral 1 designates a door frame 35 of ordinary construction, in which is hingedly mounted a swinging screen door 2, and connected at one end to one side of the door frame is a flat spring 3, the free end of which engages against the outer face of 40 the door to normally hold the same in a closed position and to automatically close the door after the same has been opened and released. Arranged against the inner face of the outer side of the door frame is a stop 45 strip 4. Substantially M-shaped springs 5 are connected at one end to the outer side of the door frame rearwardly of the strip, one of the springs being connected to the frame adjacent its upper end and the other 50 spring adjacent its lower end, the opposite end of each spring being connected to the strip 4, and the springs normally forcing the strip outwardly within the frame, one end leg of each of the springs 5 being offset

laterally as at 5^a adjacent the inner end of 55 said leg so that the major portion of the spring will be free of the frame and thus increase the efficiency of the spring. Pivotally connected at their inner ends to the top and bottom of the frame are strips 6, 60 the strips being connected to the top and bottom of the frame adjacent the inner edge of the frame, the outer ends of the strips being normally forced outwardly within the frame by the springs 7 which are of sub- 65 stantially the same construction as the springs 5. Connected to the outer face of each of the wooden strips 4 and 6 is a rubber or fabric cushioning strip 8, and the strips 4 and 6 are normally forced forwardly 70 within the frame by the tension of the springs 5 and 7, so that the door engages the cushioning strips before the door has reached its tightly closed position.

In the practical use of my improved door 75 stop, the stop strip 4 is connected to the inner face of the outer side of the door frame by the springs 5 and the stop strips 4 and 6 are pivotally connected at their inner ends to the top and bottom of the frame, the outer 80 ends of the strips 4 and 6 being supported by the springs 7. The cushioning strips 8 are connected to the outer face of each of the strips, and when the door is hingedly connected to the inner side of the door 85 frame and the door closing spring 3 is connected at one end to the frame with its free end engaged against the outer face of the door, the door will be automatically closed after the same has been opened by the tension of the spring 3 against the same. It 90 will be seen that as the tension of the spring 3 is greater than the tension of the springs 5 and 7, the door will be swung to its closed position after the same has been released, 95 and as the stop strips will have been forced outwardly within the frame after the door has been opened by reason of the tension of the springs 5 and 7, the door will engage the strips before it reaches its entirely closed 100 position so that the tension of the spring 3 will force the strips inwardly, and the tension of the springs 5 and 7 will maintain the cushioning strips 8 on the outer faces of the stop strips in engagement with the inner face 105 of the door so that insects will be prevented from passing between the strips and the door to enter the house.

From the foregoing description, it is thought to be obvious that a spring constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

Having thus fully described my invention,

what I desire to secure and claim by Letters Patent, is:—

A spring member consisting of a single length of material bent into substantially M-shape, one end leg of said member being offset laterally throughout substantially its entire length, the remaining portion of the spring being disposed in substantially the same plane, the opposite extremities of the member being provided with anchoring means.

In testimony whereof I hereunto affix my signature in the presence of two witnesses.

EDWARD RANSOM THOMPSON.
